UNITED STATES PATENT OFFICE.

ISAAC WANTLING, OF PEORIA, ILLINOIS.

DESIGN FOR AN ANCHOR FOR DRILLING-MACHINES.

SPECIFICATION forming part of Design No. 34,965, dated August 20, 1901.

Application filed July 6, 1901. Serial No. 67,373. Term of patent 14 years.

To all whom it may concern:

Be it known that I, ISAAC WANTLING, a citizen of the United States, residing at Peoria, in the county of Peoria and State of Illinois, have invented and produced a new and original Design for Anchors for Drilling-Machines; and I do hereby declare that the following is a full, clear, and exact description of the invention, which will enable others skilled in the art to which it appertains to make and use the same.

Figure 1 is a perspective view of an anchor, showing my design. Fig. 2 is a plan view. Fig. 3 is a sectional view taken on the line X-X of Fig. 2. Fig. 4 is a sectional view taken on the line Y-Y of Fig. 2.

As shown in the drawings, the leading or material features of my design consist of an anchor for drilling-machines having a flattened wedge or tapered portion 1, rectangular in shape, and 2 and 3 are extended por-

tions of the wedge lying parallel to each other and joined by a web 4, as shown. The portion 2 is shown tubular in construction, while the portion 3 is shown as an offset or driving portion of polygon shape.

5 5 is a perforation arranged in the anchor and cuts through a portion of one side of the tubular extension 2 and the web portion 4, and 6 is a loop or ring integral with the side 30 face of the offset, as shown.

Having described my invention, what I claim as new, and desire to secure by Letters Patent, is—

The design for an anchor for drilling-machines as herein shown and described. 35

In testimony whereof I affix my signature in presence of two witnesses.

ISAAC WANTLING.
